A. F. VAN DYCK

HIGH FREQUENCY APPARATUS

Filed March 31, 1922

Fig. 1.

Fig. 2.

Inventor:
Arthur F. VanDyck,
by *Albert B. Davis*
His Attorney.

UNITED STATES PATENT OFFICE.

ARTHUR F. VAN DYCK, OF SCHENECTADY, NEW YORK, ASSIGNOR TO GENERAL ELECTRIC COMPANY, A CORPORATION OF NEW YORK.

HIGH-FREQUENCY APPARATUS.

Application filed March 31, 1922. Serial No. 548,481.

To all whom it may concern:

Be it known that I, ARTHUR F. VAN DYCK, a citizen of the United States, residing at Schenectady, in the county of 5 Schenectady, State of New York, have invented certain new and useful Improvements in High-Frequency Apparatus, of which the following is a specification.

My present invention relates to apparatus 10 for controlling high frequency currents, and more particularly to apparatus for controlling, amplifying or detecting high frequency currents employed for signaling purposes.

The object of my invention is to provide 15 an apparatus of the class referred to which will be so constructed that the control or amplifying apparatus will be effectively shielded from exterior disturbing influences which would interfere with or seriously impair the 20 normal desired operation of the apparatus.

The novel features which I believe to be 25 characteristic of my invention are set forth with particularity in the appended claims, my invention itself, however, will best be understood by reference to the following description taken in connection with the accompanying drawing in which Fig. 1 is a 30 perspective view of an apparatus constructed in accordance with my invention and Fig. 2 is a similar perspective view of the same apparatus with the door thereof open.

The apparatus which I have illustrated is 35 designed for amplifying high frequency currents, being of the form commonly known in the art as a three-stage amplifier. My invention, however, is by no means limited to this specific form or type of apparatus. It may be employed wherever the apparatus is of such a nature that it is desirable to shield 40 it from disturbing influences.

As illustrated in the drawing the amplifying apparatus and the means for controlling the same is enclosed in a casing 1 preferably of metal or with a metal lining having a door 2 arranged for the convenient inspection or removal of the apparatus within the casing. The apparatus which I have illustrated within the casing comprises sockets 3, in which vacuum tube amplifiers may be 45 inserted and rheostats 4 for controlling the heating current supplied to the filaments of the vacuum tubes.

In order to provide for the convenient adjustment of the filament currents, rheostats 50 4 are provided with handles 5 which project

through openings 6 in the door 2. Since the openings in the doors must be made somewhat larger than these handles difficulty might be experienced in the operation of the apparatus by reason of the fact that external 60 electrical fields would be able to pass through these openings and interfere with the desired operation of the apparatus within the casing. To overcome this difficulty I associate with each of the handles 65 5 a disk 7 which is slightly larger than the opening in the door. I also provide contact springs 8 on the door so that when the door is closed an electrical contact is established between the casing and the disks 7. 70

In the case illustrated, the disks are mounted on the operating shafts secured to the handles 5 and marks 9 provided on the casing to provide the operator with an indication of the adjustment of the rheostats. 75 It will of course be apparent that if desired the disks may be made stationary and serve as dials in cooperation with a pointer suitably mounted on the operating handles.

I have also indicated a switch 10 operated 80 by a handle 11 for changing the circuit connections within the casing in order that the number of stages of the amplifier employed may be varied at will. The handle 11 also projects through an opening in the door and 85 this opening is closed by a disk 7 in the manner previously described.

While I have shown and described only one embodiment of my invention, it will be understood that many modifications in the 90 form of the apparatus and the nature of the control apparatus employed may be made without departing from the scope of my invention as set forth in the appended claims.

What I claim as new and desire to secure 95 by Letters Patent of the United States, is:—

1. The combination in an apparatus for controlling high frequency currents of a casing, control devices within said casing and mounted thereon, handles for adjusting 100 said control devices, a door for said casing having openings therein through which said handles project, said openings being of such size that the door can be opened without removal of the handles, and means associated 105 with said handles and located inside said door for completely closing the openings in the door when the door is closed.

2. The combination in an apparatus for controlling high frequency currents of a cas- 110

- ing, control devices within said casing and mounted thereon, handles for adjusting said control devices, a door for said casing having openings therein through which said handles project, said openings being of such size that the door can be opened without removal of the handles, said casing being arranged to shield the control devices from exterior influences, and means associated with said handles and located inside said door for completely closing the openings in the door when the door is closed. 5
3. The combination in an apparatus for controlling high frequency currents of a casing, control devices within said casing and mounted thereon, handles for adjusting said control devices, a door for said casing having openings therein through which said handles project, said openings being of such size that the door can be opened without removal of the handles, and metal disks associated with said handles and located inside said door for completely closing the openings in the door when the door is closed. 10
4. The combination in an apparatus for controlling high frequency currents of a casing, control devices within said casing and mounted thereon, handles for adjusting said control devices, a door for said casing having openings therein through which said handles project, said openings being of such size that the door can be opened without removal of the handles, said casing being arranged to shield the control devices from exterior influences, and metal disks associated with said handles and located inside said door for completely closing the openings in the door when the door is closed. 15
5. The combination in an apparatus for controlling high frequency currents of a casing, control devices within said casing, handles for adjusting said control devices, a door for said casing having openings therein through which said handles project, said openings being of such size that the door can be opened without removal of the handles, said casing being so constructed as to shield the amplifying apparatus from exterior influences and discs associated with said handles and located inside said door for completely closing the openings in the door when the door is closed. 20
6. The combination in a device for amplifying alternating currents, of a casing, amplifying apparatus within said casing and mounted thereon, control devices for said amplifying apparatus, handles for adjusting said control devices, a door for said casing having openings therein through which said handles project, said openings being of such size that the door can be opened without removal of the handles, said casing being 25 so constructed as to shield the amplifying apparatus from exterior influences and discs associated with said handles and located inside said door for completely closing the openings in the door when the door is closed. 30
7. The combination in a control apparatus, of a casing, control devices within said casing and mounted thereon, handles for adjusting said control devices, a door for said casing having openings through which 35 said handles project, said openings being of such a size that the door can be opened independently of said control devices. 40
8. The combination in a control apparatus, of a casing, control devices within said casing and mounted thereon, handles for adjusting said control devices, a door for said casing having openings therein through which said handles project, said openings being of such a size that the door can be 45 opened independently of said handles and metal disks associated with said handles for completely closing the openings in the door when the door is closed. 50

In witness whereof, I have hereunto set 85
my hand this 30 day of March 1922.

ARTHUR F. VAN DYCK.
